[57] ABSTRACT

A vertical furnace for treating material at high temperature and under high pressure has a stand into which a cylindrical pressure chamber is introduced. This stand is formed of a high pressure cylinder with top and bottom end closures which project into the cylinder. A furnace chamber is formed within the pressure cylinder by two hat-shaped parts with insulating material between them. These parts rest on an annular portion of the bottom closure. The inner part of the bottom closure is removable for charging the furnace.

**CYLINDRICAL ELONGATED FURNACE FOR
TREATING MATERIAL AT HIGH TEMPERATURE
AND UNDER HIGH PRESSURE**

BACKGROUND OF THE INVENTION

1. Field of the Invention

The present invention relates to a cylindrical, elongated furnace for treating material at high temperatures up to 1500° C and high pressures, preferably 500 bar and above.

2. The Prior Art

Certain high speed steel alloys are extremely difficult, or almost impossible, to manufacture by means of conventional metallurgical methods of melting, since a billet produced by means of casting acquires an unfavorable coarse-grained structure with considerable segregation. Because the alloying constituents separate during the casting and solidifying processes, different parts may acquire a different composition. An important field of use for furnaces of the type to which the invention relates is the manufacture of high speed steel ingots by hot isostatic compression or pressure sintering a billet of powder of the desired composition which is enclosed in a metal capsule. By means of pressure sintering, the sintering can be carried out at lower temperatures than when it is performed at atmospheric pressure or under vacuum, but it is most important that the alloying constituents retain their places inside the ingot and that the powder grains are compressed by the pressure to form an extremely dense and pore-free product. This makes the material extremely tough and durable. It may be mentioned, for example, that a high speed steel drill of pressure-sintered starting material may be up to five times as durable as a drill of conventionally manufactured material having otherwise identical composition.

Pressure furnaces comprise a furnace chamber enclosed in a pressure chamber. The pressure chamber must be kept cool enough so that its strength is not reduced. The walls may even have to be cooled. The furnace chamber must therefore be effectively insulated from the pressure chamber. Because of the high pressure, the pressure medium has high density and extremely high thermal capacity. Argon, which is a suitable easily available and inexpensive pressure medium, has also extremely low viscosity, only 4 to 5 times that of air at atmospheric pressure at the density and temperature in question, and is thus extremely movable. In view of the considerable capacity of the pressure medium to transport heat, it is important for the operation of the furnace that the insulation around the furnace chamber be of such a design that the least possible convection is obtained between the furnace chamber and the space between its insulation and the walls of the pressure chamber.

In one conventional pressure furnace, the furnace chamber is surrounded by a cylindrical insulating sheath which is suspended in the upper end closure of the pressure chamber and joined to this end closure in a gas tight manner. In this furnace a lid projecting into the insulating sheath is also suspended in the upper end closure. For pressure equalization there must be a connection in this construction between the hot furnace chamber and the space in and above the insulating lid. There is thus a connection between the furnace chamber and a cold surface on the lower side of the

upper end closure. There is thus a cold space above the hot furnace chamber and a connection through which hot, light pressure medium will flow. This connection may cause heat losses and induce heating of the upper end closure and adjacent parts of the pressure cylinder.

SUMMARY OF THE INVENTION

According to the invention, the insulation surrounding the furnace chamber comprises an insulating part in the shape of a sealed lid which is formed of at least two hat-shaped parts, closed at the top, and having insulation between them. This hat-shaped insulating part may be suspended in the upper end closure or be supported by the lower end closure. In the latter case, the lower end closure must be divided into an annular part which is permanently arranged in the high pressure cylinder. The hat-shaped insulating part is supported by this annular part, the opening of which is the charging opening. The cylindrical part of the hat-shaped insulation is preferably constructed in a manner known per se with three metal tubes arranged one inside the other with insulation between them, the innermost tube being made of a material having a lower coefficient of thermal expansion than the material in the surrounding tubes. In the hat-shaped insulation, two cylindrical tubes and intermediate insulation and a lid may together form a hat-shaped part which surrounds an inner hat-shaped part and intermediate insulation. The spaces in the insulation between the metal tubes communicate with other spaces inside the pressure chamber by means of pressure equalizing openings.

Heating elements to heat the furnace chamber are placed inside the hat-shaped insulation and are supported by the same annular end closure part as the insulation. All bushings for the wiring of the heating elements and supply conduits for pressure medium are arranged in the annular part of the end closure.

Besides the improvement of the heat insulation, the invention means that the insulation, the heating elements and the supporting, annular end closure form an exchangeable unit which, upon a breakdown, can easily be removed from the pressure cylinder and replaced by a reserve unit. This is an extremely important advantage in industrial operation since pressure furnaces and their auxiliary equipment are expensive and are normally part of series of production equipment with pre-heating furnaces and the like, where an interruption of operation is extremely expensive.

BRIEF DESCRIPTION OF THE DRAWINGS

The invention will be further described with reference to the accompanying drawings. FIG. 1 shows a side view of a furnace unit, partly in section, and FIGS. 2 and 3 are vertical sections through the upper and lower parts, respectively, of a pressure chamber with insulation surrounding a furnace chamber enclosed in the pressure chamber.

**DESCRIPTION OF THE PREFERRED
EMBODIMENTS**

In the drawings 1 designates a press stand which is movable between the position shown in FIG. 1 and a position where it surrounds the high pressure chamber 2. The press stand is of the type consisting of two yokes

3 and 4, intermediate spaces 5 and a sheath 6 holding them together. The stand is supported by wheels 7 running on rails 8. The high pressure chamber is carried by a pillar 9. The high pressure chamber is constructed of an inner tube 10 and a sheath 11 surrounding this inner tube, as well as end rings 12 which axially hold together the sheath 11 and provide attachments for brackets 13 by means of which the high pressure chamber 2 is attached to the pillar 9. The chamber 2 has an upper end closure 14 which projects into the tube 10 of the high pressure chamber. Between the tube and the end closure is a sealing ring 15 which is supported by a triangular support ring 16 and which is held in position by a holding ring 17. This ring is attached in the lid 14 by means of bolts 18.

The pressure chamber has a lower, divided end closure consisting of an outer annular part 19, removable but permanently attached, projecting into the tube 10, and a bottom 20 projecting into the part 19. A ring 21 rests on the annular part 19 of the end closure. This ring is attached to the part 19 by means of bolts, not shown, and supports the main part of the insulating casing which surrounds a furnace chamber 22 where a billet 23 is being treated. The insulating casing comprises a combined hat-shaped insulating part 24. This comprises an inner hat-shaped part consisting of a metal tube 25 which at its lower end is shaped with a flange 26 and at its upper end is closed by a lid 27 having an upwardly directed flange 28. The tube 25 and the lid 27 are joined together in a gas tight manner by means of a weld 29. The insulating part 24 also comprises an outer hat-shaped part consisting of two tubes 30 and 31, insulating material 32 between the tubes, the rings 33 and 34 at the ends of the tubes and the lid 35. The tube 25 is made of a material having a lower coefficient of thermal expansion than the tubes 30 and 31. The interior of tube 25 constitutes the furnace chamber. The tubes 30 and 31 and the lid 35 are joined by welds 36 to the ring 34 in a gas tight manner. The tube 30 is joined at its lower end by the weld 37 to the ring 33, while the tube 31 is freely movable at its lower end in axial relation to the ring 33. The space between the two hat-shaped parts is filled with an insulating material 38. The spaces filled with insulating material communicate with surrounding spaces through pressure-equalizing openings 39 and 40 at the lower parts of the spaces. The whole hat-shaped insulating part and a holding ring 41 for the seal 42 is bolted to the ring 21 by means of a number of bolts 43. The seal 42 which seals between the tube 10 and the annular part 19 of the end closure is supported by a triangular support ring 44.

The bottom 20 which projects into the ring 19 is provided with a seal 45 which is supported by a triangular support ring 46 and held in place by a holding ring 47 provided with an internal thread cooperating with a thread in the innermost part of the lid. A billet 23 to be treated in the furnace is supported by a bottom part of insulating material joined to the bottom 20, this part consisting of a tube 48 with a flange 49. The tube 48 is filled with an insulating material 50. It is attached to the part 20 by engagement of the flange 49 by the holding ring 47.

Inside the insulating casing 24 which surrounds the furnace chamber 22 are electric heating elements 51 supplied through conductors 52 which are connected

to bushings 53 in the annular part 19 of the end closure. Between the bushing 53 and the ring 19 is an insulating sleeve 54 and an insulating washer 55. The bushing is fixed in the ring 19 by a nut 56. The bushing 53 opens in a radial slot 57 and is connected to a conductor 58 by means of a nut 59.

In the space between the tube 25 and the tube 48 is an insulating ring which insulates the annular parts 19 and 21 of the end closure from the furnace chamber 10 22. This insulating ring consists of two short metal tubes 60 and 61 and intermediate insulating material 62. The tubes are provided with flanges 63 and 64 and attached to the ring 21 by means of the holding ring 41 and bolts 65, respectively. The furnace chamber 22 communicates through the channel 67 in the ring 20 with the gap 66 between the tube 10 and the insulating casing around the furnace chamber.

The annular part of the lower end closure, which supports the hat-shaped insulating part and the heating elements surrounding the furnace chamber 22 is normally fixedly attached in the pressure chamber, but is removable therefrom. The attachment means are not shown. The bottom 20 of the end closure, with its insulating bottom part, however, is suspended in a lifting mechanism by means of which the furnace is charged. The bottom 20 is joined by a bracket 70 to a guiding sleeve 71 which slides on a guide rail 72. The part 20 of the end closure can be raised and lowered by means of 25 an operating cylinder 73, the piston rod 74 of which is attached to the bracket 75 on the sleeve 71. Supply conduits for pressure medium are not shown. Through-holes for pressure medium are also suitably arranged in the ring 19.

35 By constructing the insulating sheath with two hat-shaped parts of metal completely closed at the top, all risk of the formation of convection currents between the furnace chamber itself and the space between the insulating casing and the cold walls of the pressure chamber and the upper end closure are eliminated. By making the insulating casing, heating elements and annular part of the end closure as a single, replaceable unit, these parts of the furnace which are most subject to disturbances in operation can be quickly replaced if there is an accident and the damaged unit can be repaired under more favorable conditions at a service workshop by specially trained personnel. Another advantage with the embodiment according to the invention is that the unit of insulation and heating elements can be removed and inserted in the pressure chamber with the help of the same lifting device as that used for charging the furnace. The ring 19 of the end closure is loosened from the annular part of the pressure chamber with the bottom 20 pressed in, after which the bottom 20 with the unit consisting of the ring 19 and insulation and heating elements, is lowered with the help of the operating cylinder 73 and a new unit is inserted with the help of the operating cylinder. Separate lifting means are therefore unnecessary.

I claim:

1. Vertical furnace, preferably for hot isostatic compaction of powder bodies, comprising a stand, a cylindrical pressure chamber suspended in the stand and comprising a high pressure cylinder and top and bottom end closures projecting into the pressure chamber, means forming a furnace chamber within the pressure

cylinder and insulation arranged between the furnace chamber and the walls of the pressure chamber comprising an insulating part in the shape of a sealed lid which is formed of at least two separate parts each comprising a transverse portion and a cylindrical wall extending downwardly from the periphery of said transverse portion, said parts being closed in a gas-tight manner at the top and with insulation filling the space between the transverse portions.

2. Furnace according to claim 1, in which the bottom end closure includes an annular part projecting into the pressure chamber forming part of a divided lower end closure, the opening of said annular part constituting the charging opening, said separate parts being supported by said annular part.

3. Furnace according to claim 2, in which one separate part comprises two tubular parts with insulation therebetween and a gas-tight lid connected to these two tubular parts, and the other separate part is closed at the top and arranged inside the lid.

4. Furnace according to claim 2, having inside the

inner separate insulating part a heating element which rests on the annular part of the end closure.

5. Furnace according to claim 4 having bushings for supply of energy to the heating element arranged in the annular part of the lower end closure.

6. Furnace according to claim 1, in which the cylindrical part of the insulating part comprises at least three tubular parts arranged one inside the other with insulating material therebetween.

10 7. Furnace according to claim 6, in which the material of the inner tubular part has lower coefficient of thermal expansion than the material of the surrounding tubes.

15 8. Furnace according to claim 6, in which a lid is joined to the two outer tubular parts constituting therewith one of said separate parts.

9. Furnace according to claim 6, having pressure-equalizing openings connecting between the tubular parts with other spaces inside the pressure chamber.

THE PATENT IS HEREBY AMENDED AS
INDICATED BELOW.

Matter enclosed in heavy brackets **[ ]** appeared in the patent, but has been deleted and is no longer a part of the patent; matter printed in italics indicates additions made to the patent.

AS A RESULT OF REEXAMINATION, IT HAS
BEEN DETERMINED THAT:

Claim 4 is cancelled.

Claims 1-3, 5, and 6 are determined to be patentable as amended.

Claims 7-9, dependent on an amended claim, are determined to be patentable.

1. Vertical furnace, preferably for hot isostatic compaction of powder bodies, comprising a stand, a cylindrical pressure chamber suspended in the stand and comprising a high pressure cylinder and top and bottom end closures projecting into the pressure chamber, means forming a furnace chamber within the pressure cylinder and insulation arranged between the furnace chamber and the walls of the pressure chamber com-

prising an insulating part in the shape of a sealed lid which is formed of at least two separate parts each comprising a transverse portion and a cylindrical wall extending downwardly from the periphery of said transverse portion, said parts being closed in a gas-tight manner at the top and with insulation material filling the space between the transverse portions and the space between said cylindrical walls, an annular part resting on said lower end closure, a heating element disposed within the insulating part, said at least two separate parts and said heating element at the lower ends thereof being secured to said annular part.

2. Furnace according to claim 1, in which the bottom end closure includes an **annular part** **[projecting into the pressure chamber forming]** **[forms part of a divided lower end closure, the opening of said annular part constituting the charging opening]**, said separate parts being supported by said annular part.

3. Furnace according to claim 2, in which one separate part comprises two tubular parts with insulation material therebetween and a gas-tight lid connected to these two tubular parts, and the other separate part is closed at the top and arranged inside the lid.

5. Furnace according to claim **[4]** 1 having bushings for supply of energy to the heating element arranged in the annular part of the lower end closure.

6. Furnace according to claim 1, in which the cylindrical walls **[part]** of the insulating part **comprise** **[comprises]** at least three tubular parts arranged one inside the other with insulating material therebetween.
